(57) **CLAIM**

The ornamental design for a pair of footwear soles, as shown and described.

DESCRIPTION

FIG. 1 is a lateral perspective view of one of the pair of footwear soles;

FIG. 2 is a medial perspective view of the footwear sole of FIG. 1;

FIG. 3 is an anterior (front) view of the footwear sole of FIG. 1;

FIG. 4 is a posterior (rear) view of the footwear sole of FIG. 1;

FIG. 5 is a medial view of the footwear sole of FIG. 1;

FIG. 6 is a lateral view of the footwear sole of FIG. 1;

FIG. 7 is a top view of the footwear sole of FIG. 1; and,

FIG. 8 is a bottom view of the footwear sole of FIG. 1.

The embodiment of the footwear sole shown in FIGS. 1–8 is for a left foot. The embodiment of the footwear sole for a right foot is a mirror image of the embodiment shown in FIGS. 1–8 about a sagittal plane of a human body.

The dash dot dash broken lines depict the boundary of the claimed invention and areas outside of the dash dot dash broken lines form no part of the claim. The evenly dashed broken line depicts a feature of the footwear sole that is not part of the claimed invention.
